UNITED STATES PATENT OFFICE.

ELIAS JOHNSON AND SIMON PETERSON, OF NEWHALL, IOWA.

CYLINDER AND PISTON CONSTRUCTION.

Application filed April 13, 1922. Serial No. 552,094.

To all whom it may concern:

Be it known that we, ELIAS JOHNSON and SIMON PETERSON, citizens of the United States, residing at Newhall, in the county 5 of Benton and State of Iowa, have invented certain new and useful Improvements in Cylinder and Piston Constructions, of which the following is a specification.

The present invention relates to improvements 10 in internal combustion engines, and has particular reference to the construction of the piston and cylinder of such engines.

An important object of the invention is to so construct the piston and its coating 15 cylinder, that deposits of carbon upon the sides of the cylinder are removed, the leakage of compression reduced to the minimum, with the obvious advantages, and to provide a construction which is simple and 20 strong.

Other objects and advantages of the invention will be apparent during the course of the following description.

In the accompanying drawings forming a 25 part of this specification, the figure is a central longitudinal sectional view through a piston cylinder embodying the invention.

In the drawings, wherein for the purpose of illustration is shown a preferred embodiment 30 of our invention, the numeral 1 designates the cylinder of an internal combustion engine. This cylinder may be equipped with a head 2.

The numeral 3 designates a piston mounted 35 to reciprocate within the cylinder, which piston is preferably of the hollow type with an upper closed head or end 4. The piston is preferably equipped with packing rings 5.

Preferably formed integral with the upper 40 end of the piston and its head 4 is an annular flange 6, the outer wall of which is cylindrical and constitutes a continuation of the outer wall of the piston. This increases the contact area between the piston 45 and cylinder and serves to prevent leakage of compression. It is preferred that the flange 6 have its face 7 inclined, and flaring outwardly toward the upper end of the flange. This sharp edge serves to effectively 50 scrape or remove carbon deposits from the interior of the cylinder. The numeral 8 designates a coating annular flange, preferably formed integral with the upper end 55 of the cylinder, upon the interior thereof. This flange is provided upon its bottom with a recess 9, tapered or V-shaped in cross-

section, and adapted to accurately receive and fit the flange 6, upon the up-stroke of the piston. When the piston has reached the end of its upward movement, it will be seen that a tight joint is effected between the substantially contacting faces of the flanges 6 and 8, and this joint will prevent leakage of compression, to a considerable extent.

It is obvious that the invention is in no sense restricted to the precise location of the flange 8, as this may vary somewhat with the construction of the engine, taking into consideration the location of the valves, etc.

It is to be understood that the form of the invention herewith shown and described is to be taken as a preferred example of the same, and that various changes in the size, shape, form and arrangement of parts may be resorted to without departing from the spirit of the invention or the scope of the subjoined claims.

Having thus described our invention, we claim:

1. In an internal combustion engine, a cylinder provided with an interior flange, said flange being provided upon one side with a recess, the outer wall of said recess being cylindrical and forming a continuation of the inner wall of the cylinder, and a piston mounted to reciprocate within the cylinder and provided at one end with a flange integral therewith, said flange projecting longitudinally beyond the piston and adapted to enter said recess in the first named flange, the outer wall of the piston flange being cylindrical and forming a continuation of the outer wall of the piston.

2. In an internal combustion engine, a cylinder provided with an interior flange, said flange being provided with a recess upon one side, which recess is tapered in cross section, the outer wall of the recess being cylindrical and forming a continuation of the inner wall of the cylinder, and a piston mounted to reciprocate within the cylinder and provided near one end with a rigid flange projecting longitudinally beyond the same, said rigid flange being tapered in cross section to fit within said recess, said rigid flange having its outer wall cylindrical and forming a continuation of the outer wall of the piston.

3. In an internal combustion engine, a cylinder provided upon its inner wall with

an annular flange integral therewith, said annular flange having an annular recess which is substantially V-shaped in cross-section, one wall of the recess coinciding with the wall of the cylinder and the other wall being inclined with relation thereto, and a piston to reciprocate within the cylinder and provided at its closed end with a flange integral therewith, said flange being substantially V-shaped in cross-section

with its outer wall parallel with the inner wall of the cylinder and its inner wall inclined, the flange having its forward end sharpened and said flange being adapted to enter said recess.

In testimony whereof we affix our signatures.

ELIAS JOHNSON.
SIMON PETERSON.
